UNITED STATES PATENT OFFICE.

ALFRED HALL, OF WORCESTER, MASSACHUSETTS, AND ELDRIDGE D. G. BROUSE, OF TORONTO, ONTARIO, CANADA; SAID BROUSE ASSIGNOR TO SAID HALL.

STAMP-AFFIXER.

1,281,353.

Specification of Letters Patent. Patented Oct. 15, 1918.

Application filed January 22, 1915. Serial No. 3,749.

To all whom it may concern:

Be it known that we, ALFRED HALL, of Worcester, in the county of Worcester and State of Massachusetts, and ELDRIDGE D. G. BROUSE, of Toronto, and Province of Ontario, Canada, have invented certain new and useful Improvements in Stamp-Affixers, of which the following is a specification.

Our invention has reference to improvements in stamp or label affixing machines.

The primary object of the invention is to provide means for preventing the strip of stamps or labels from adhering to their supporting means. Other objects of the invention will appear from the following description.

The invention consists in a stamp lifting and stripping device for accomplishing this object. The invention further consists in such other novel features of construction, operation and combination of parts, as shall hereinafter be described and pointed out in the claims.

Referring to the drawing:—

Fig. 1 represents a longitudinal sectional view, partly in elevation, of a stamp affixer embodying our invention.

Fig. 2 represents a sectional plan view taken on the plane 2—2 of Fig. 1.

Fig. 3 represents a fragmentary sectional view taken on the plane 3—3 of Fig. 2.

Fig. 4 represents a view corresponding to Fig. 3 but with the mechanism shown in a different position.

Figs. 5 and 6 are enlarged fragmentary sectional views taken on the plane 3—3 of Fig. 2, illustrating two operations of the lifting and stripping device.

Fig. 7 represents a fragmentary sectional view taken on the plane 7—7 of Fig. 4.

Fig. 8 represents a view in perspective of a wick extending through a frame which may be used to apply it to the moistening tank.

Like reference characters designate corresponding parts throughout.

The type of affixer represented in the drawings is provided with the casing 10, having the stamp discharging orifice 11, 50 which is in the path of the presser foot 12 on the lower end of the plunger 13. The latter is adapted to be reciprocated in the bearing 14 secured to the inside of said casing; the down stroke thereof being accom-

plished by downward pressure on the knob 55 15 and is returned by action of the spring 16 suitably arranged within the plunger 13 in a well known manner. On the end of the lug 18 projecting from said plunger is the stud or roller 19 which engages with 60 the cam slot 20 in the carriage actuating lever 21, pivoted at 22 on the casing and its lower end is provided with the slot 23. The latter engages the pin 24 of the carriage 25 in which is pivoted one end of the fingers 65 26 pressed downwardly by the leaf spring 27. Said fingers are normally disengaged from the supporting table 38, hereinafter described, by their under cam shaped edge engaging the pin 26^a extending between the 70 pair of plates 30. The carriage 25 is provided with the rollers 28 which engage horizontal slots 29 in the plates 30 connected by the tie-rod 31, and bar 32. Secured at its rear end to the latter is the guiding plate 33 75 made of resilient sheet metal, and is cut away to form the tongue 34, and pressure heads 35, 35. The latter are provided with the transverse slots 36, 36, and stamp contacting V shaped ribs 37 on their bottom 80 surfaces. Adjacent and partially beneath said guiding plate is the strip supporting plate or table 38 made of resilient sheet metal and secured at its rear end to the stud 39 projecting from the casing. Said table 85 38 is preferably provided with three longitudinally extending inverted V shaped ribs 40 and apertures 41, 41. The latter are adapted to receive therethrough the upwardly projecting strip lifting and stripping members 42, 42, having the beveled edges 43. The members 42, 42 are a part of the head 44 which projects in a plane at right angles to the plane of the lever 45 and is a part thereof. Said lever is pivoted at 90 one end 46 to the casing, and its other end 47, being bent at right angles, normally bears on the presser foot and is sustained in this position during a portion of the movement of the presser foot by the lug 50 secured to the top of the presser foot and by the spring 51, coiled about the stud or screw 52 projecting from the casing and having one end thereof engaging said lever and the other bearing against the front of the casing. Said lever and spring are guided by the strap 55 secured to said casing.

Beneath the table 38 is the tank 60 pro-

vided with the removable wick 61 at the end of said table. Said wick may be applied to said tank by securing a frame 62 thereon by means of indentations 63 in the frame and 5 then pressing the wick and shank of the frame down into the neck 64 of the tank until the flange 62^a of the frame engages the top of said neck. (Figs. 8 and 6.)

On the end of the tank is secured the stationary 10 knife 65 having the two upwardly projecting guides 66, which guide the knife 67 on the presser foot 12.

The operation of that part of the affixer, which forms no part of the present invention 15 will be but briefly described herein, while the operation of that part of the affixer which is a part of the present invention will be fully described.

The roll of stamps S to be affixed is placed 20 on the stud 56 and the free end thereof is passed beneath the flanged roller 57 and between the supporting table 38 and guiding plate 33 in the usual manner.

At the start of the downward movement 25 of the plunger 13 the lever 45 is swung downwardly until its end 47 disengages from the lug 50 and its head 44 strikes the top of the tank 60. Said lever is sustained in the latter position by the spring 51. The carriage 30 is then moved forward through the mechanism connecting it with the plunger, and the fingers 26 disengage from the pin 26^a and their pointed ends engage a row of perforations between two connecting stamps, 35 forcing the strip of stamps forward until a complete stamp has been fed over the wick 61 and stationary knife 65. The stamp is then cut off by the knife 67 co-operating with the knife 65, and is affixed by the pressure 40 foot 12. On the return stroke of the plunger 45 the carriage 25 is returned to its initial position and close to the completion of its stroke the fingers 26 engage the pin 26^a thereby lifting the ends of said fingers 45 slightly above the strip of stamps. During 50 the latter part of the return stroke of said plunger, the end 47 of the lever 45 is engaged by the presser foot 12 and lug 50 which carries said lever back to its initial position.

This return movement of the lever 45 causes the lifting and stripping members 42 to extend through the apertures 41 in the table 38 which raises the forward end portion of the strip of stamps out of contact with the table 55 and wick 61, and the head 44 raises the table 38.

The fact that the forward end of the strip of stamps is raised above the table after each stamp is affixed is the most important feature of this invention, as it has been found in practice that merely raising the table so as to bring the stamps out of contact with the wick allows the moisture on the portion of the stamps that was in contact with the wick to soak back which causes the strip to

adhere to the forward end of the table. With the present device, however, even though the strip does adhere slightly to the table, while the plunger is down, is immaterial, as the strip will be immediately 70 stripped from the table on the up stroke of the plunger.

Another important feature of the invention is the construction of the guiding plate 33, which has sufficient resiliency to cause its 75 heads 35 to give the right pressure to the stamps as they pass over the wick. The slots 36 prevent any moisture that might collect on said heads from creeping back. The tongue 34 which continually presses on the 80 strip has a sort of a ratchet effect to prevent the stamps from working rearwardly.

While it is preferred to employ the specific construction and arrangement of parts shown and described, it will be understood 85 that this construction and arrangement is not essential excepting so far as specified in the claims and may be changed or modified without departing from the broader features of the invention.

Having thus described our invention we claim as new and desire to secure by Letters Patent:

1. In a stamp affixer, the combination of a support for a strip of stamps, means for moving said support to effect the raising and lowering of the strip of stamps, mechanism for detaching a stamp from the strip and affixing it, with means for lifting the forward end portion of the strip out of contact with said support after the completion of said detaching and affixing operations.

2. In a stamp affixer, the combination of a support for a strip of stamps, means for moving said support to effect the raising and lowering of the strip of stamps, mechanism for moistening, detaching and affixing a stamp from the strip, with means for separating the forward end portions of the strip and said support after said affixing operation.

3. In a stamp affixer, the combination of a support for a strip of stamps, means for moving said support to effect the raising and lowering of the strip of stamps, mechanism for moistening, detaching and affixing a stamp from the strip, means for separating the forward end portions of the strip and said support after said affixing operation, and means for causing said end portions to contact at the start of the operation of said mechanism.

4. In a stamp affixer, the combination of a support for a strip of stamps, mechanism for feeding, moistening, detaching and affixing a stamp from the strip, a guiding member for sustaining the strip in contact with said support while said strip is being fed, with means for lifting the forward ends of the strip and said guiding member away

from the corresponding end of said support after the completion of the affixing operation.

5. In a stamp affixer, the combination of 5 a table for supporting a strip of stamps, mechanism for moistening, detaching and affixing a stamp from the strip, a lifting member disposed beneath apertures in the forward end of said table, with means for 10 raising said lifting member to extend the latter through said apertures after the completion of the affixing operation.

6. In a stamp affixer, a support for a strip of stamps, a moistening wick adjacent 15 the forward end of said support, means for feeding the strip over said wick, means for pressing the strip into contact with said wick while it is being fed, means for lifting the strip out of contact with said 20 wick and the forward end portion of said support after a stamp has been fed over said wick with correlative means for detaching the stamp from the strip and affixing it.

7. In a stamp affixer, a support for a strip 25 of stamps, moistening means adjacent the forward end thereof, a guiding member for sustaining the strip in contact with said moistening means and said support, said guiding member consisting of a resilient plate 30 secured at its rear end to a stationary member and, provided with a transverse aperture near its forward end, means for intermittently feeding the strip the length of a stamp, means for lifting the strip and said guiding 35 member out of contact with the moistening means and said support after a feeding operation, with means for detaching a stamp from the strip and affixing it.

8. In a stamp affixer, a support for a 40 strip of stamps, means for feeding the strip over said support, moistening means adjacent the forward end of said support, a guiding member for the strip provided with a pair of downwardly pressing heads to 45 press the strip on said moistening means while it is being fed, transverse apertures in

each head, with means for detaching a stamp after it has been fed over said moistening means and affixing it.

9. In a machine of the character described, the combination of a support for a strip, moistening means, means for moving said support to effect the raising and lowering of the strip relative to said moistening means, means for feeding the strip, 55 means for detaching a portion of the strip, with means for lifting the forward end portion of the strip out of contact with said support at the completion of said feeding operation. 60

10. In a machine of the character described, the combination of a support for a strip, moistening means, means for moving said support to effect the raising and lowering of the strip relative to said moistening means, means for feeding the strip, 65 means for detaching a portion of the strip, with means including a lifting member 42 for lifting the forward end portion of the strip out of contact with said support at the completion of said feeding operation. 70

11. A stamp affixer comprising a support for a strip of stamps, means for feeding, moistening, detaching, and affixing a stamp from the strip, with means for engaging the 75 strip to separate the latter and said moistening means, said means for engaging the strip being out of contact with the strip when the latter is in contact with said moistening means. 80

In testimony whereof we have affixed our signatures, each in the presence of two witnesses.
